(57) **CLAIM**

The ornamental design for a dual-layer shapewear for men as shown and described.

DESCRIPTION

FIG. 1 is a top perspective view of a dual-layer shapewear for men showing my new design;

FIG. 2 is an exploded view of FIG. 1, showing the internal layer and outer layer being separated.

FIG. 3 is a top perspective view of the outer layer of the dual-layer shapewear for men;

FIG. 4 is a front view thereof;

FIG. 5 is a rear view thereof;

FIG. 6 is a left view thereof;

FIG. 7 is a right view thereof;

FIG. 8 is a top view thereof;

FIG. 9 is a bottom view thereof;

FIG. 10 is a top perspective view of the internal layer of the dual-layer shapewear for men;

FIG. 11 is a front view thereof;

FIG. 12 is a rear view thereof;

FIG. 13 is a left view thereof;

FIG. 14 is a right view thereof;

FIG. 15 is a top view thereof; and,

FIG. 16 is a bottom view thereof.
